UNITED STATES PATENT OFFICE.

CHARLES H. GUNN, OF OAKLAND, CALIFORNIA.

TOILET FLUSH.

Application filed September 5, 1922. Serial No. 586,308.

To all whom it may concern:

Be it known that I, CHARLES H. GUNN, a citizen of the United States, residing at Oakland, county of Alameda, State of California, have invented certain new and useful Improvements in Toilet Flushes; and I do declare the following to be a full, clear, and exact description of the same, reference being had to the accompanying drawings, and 10 to the characters of reference marked thereon, which form a part of this application.

This invention relates to the plumbing art, and particularly to devices for flushing toilets. The object of the invention is to 15 provide an efficient flush which will give a quick and adequate supply of water under pressure; one which will be leak-proof; cannot become air bound; be economical and accurate in the amount of water used; and 20 finally one which can be economically constructed and easily and quickly installed for use and easily kept in repair.

A further object of the invention is to 25 produce a simple and inexpensive device and yet one which will be exceedingly effective for the purposes for which it is designed.

These objects I accomplish by means of 30 such structure and relative arrangement of parts as will fully appear by a perusal of the following specification and claims.

In the drawings similar characters of 35 reference indicate corresponding parts in the several views:

Fig. 1 is a side elevation of a toilet showing my improved flush installed ready for use.

Fig. 2 is a vertical cross sectional view taken on a line 2—2 of Fig. 1.

Fig. 3 is a cross sectional view taken on a line 3—3 of Fig. 1.

Fig. 4 is a sectional view taken relatively on a line 4—4 of Fig. 2.

Fig. 5 is a sectional view taken relatively on a line 5—5 of Fig. 3.

Referring now more particularly to the characters of reference on the drawings, the numeral 1 designates the flush tank of desired shape and size into which enters the 50 water supply inlet pipe 2.

The discharge outlet 3 is relatively larger than the inlet 2, and said outlet 3 opening into the still larger flush pipe 4. The pipe 4 is threaded into the bottom of the tank 1 and has a cross head 3^a in which is formed the outlet 3, surrounding which is an up-

turned flange 3^b forming the seat for the closure valve 5, having a gasket 5^a, the valve and gasket being held in position on the bottom of a float 6 by means of bolt 6^a 60 extending through the gasket, valve and float.

Two upstanding pipes 7 are mounted on the cross head 3^a and extend through the tank 1 and act as guides for the float 6 which is grooved or orificed as at 6^b for the purpose. These pipes 7 also act as guides for rods 8 which extend into the outlet pipe 4. On the lower end of said rods is a cross head 9 with springs 10 interposed between 70 the cross heads 9 and 3 and around the rods 8.

The cross head 9 carries a valve releasing pin 11 for a purpose as will presently appear.

The head 12 of the tank 1 has a counter sunk interiorly threaded collar 13 terminating in an annular seat 14. A plate 15 rests on said seat with an intermediate gasket 15^a to make a water and air tight joint. 80

The pipes project through holes 16 in the plate 15 surrounded by conical rubber gaskets 16^a held in position by a plate 17 to make water and air tight joints. The plates 15 and 17 are clamped into position against 85 their gaskets by a hollow nut 17^a threaded into the collar 13.

18 designates a support extending upwardly from the plate 17 in which is pivoted the operating handle 19. Links 20 connect the handle 19 with clamps 21 into which are clamped the rods 8. A stop screw 22 mounted on the top of the plate 17 limits the movement of the clamps and consequently the rods 8.

The float 6 is nicely and arbitrarily balanced so that, after a complete flushing the weight of the water, combined with the suction through the outlet 3 will pull the valve 5 closed and hold it firmly in that 100 position while the tank fills again.

To flush the tank, the operator presses the handle 19. This pulls on the rods 8 and the cross head 9 carries the releasing pin 11 into control with the float valve and lifts 105 it from the valve seat 3^b. The rush of the water through the opening 3 upsets the nice balance of and suction against the float 6 and it rides or floats quickly to the top of the water, guided by the pipes 7. The float has a pointed end 6^c which aids it in cutting 110 quickly through the water.

The springs 10 return the rods 8 and co-operating parts back to normal position and as the water flushes out the valve again, closes over the outlet 3 whereupon the operation can be repeated.

Quick discharge of the water is had by reason of the pressure in the tank, which is air tight as described, and also as the discharge is taking place air is readily drawn 10 into the discharge pipe 4 through the pipes 7, thus obviating any tendency to vacuum.

The flushing apparatus as above described cannot become air bound since the intake is entirely separate from the outlet.

15 The parts of the device are so balanced and proportioned that the float travels clear to the top of the tank and back again with each flush so the exact amount of water is used each time.

20 The pin 11 has a rubber tip 11^a to engage the end of the bolt 6^a and is thread jointed at 11^b to admit of adjustment of its length.

The upper end of the member 11 is nearly as large as the outlet 3, so that the water 25 cannot begin to flush out until the float has been raised by the pin 11 and the latter has dropped back to its normal position.

This gives the float a chance to get far enough away from its seat to eliminate the 30 chance of the drag of the water reseating the float before the tank has been emptied.

From the foregoing description it will be readily seen that I have produced such a de-

vice as substantially fulfills the objects of the invention as set forth herein.

35

While this specification sets forth in detail the present and preferred construction of the device, still in practice such deviations from such detail may be resorted to as do not form a departure from the spirit 40 of the invention, as defined by the appended claims.

Having thus described my invention, what I claim as new and useful and desire to secure by Letters Patent is:

45

1. A toilet flushing apparatus comprising a tank having an inlet and an outlet, a float-controlled valve for the outlet a pipe below the outlet, pipes communicating with the outlet pipe and extending longitudinally 50 through the tank, and means operable within and through the pipes for controlling the valve, the floating action of the valve being guided by the pipes.

55

2. A toilet flushing apparatus comprising a tank having an inlet and an outlet, a float over the outlet, a valve-pad on the lower end of the float adapted to close the outlet, and pipes projecting upwardly in the tank at the sides of the outlet, the sides 60 of the float being vertically grooved to fit the pipes, whereby the latter form guides for the float.

In testimony whereof I affix my signature.

CHARLES H. GUNN.
